(57) **CLAIM**

The ornamental design for a kick scooter, as shown and described.

DESCRIPTION

FIG. 1 is a perspective view of the kick scooter showing our new design;

FIG. 2 is a front view thereof;

FIG. 3 is a back view thereof;

FIG. 4 is a top view thereof;

FIG. 5 is a bottom view thereof;

FIG. 6 is a right-side view thereof; and,

FIG. 7 is a left-side view thereof.

The broken lines are for the purpose of illustrating portions of the kick scooter that form no part of the claimed design.
